REFRIGERATION SYSTEM FOR DISPLAY CABINETS, FOOD STORAGE CABINETS, AND THE LIKE

Adam Boren, 300 Deal Lake Drive, Asbury Park, N.J.
Filed May 16, 1962, Ser. No. 195,297
7 Claims. (Cl. 62—278)

This invention relates to a novel system of refrigeration for display cabinets, food storage cabinets, and the like, 10 remotely located, and with widely different temperature requirements.

In accordance to the present invention a central unit supplies air through two lines to the remote cabinets: one supply line being cold, as below -20° F.; the other warm, as above $+80^{\circ}$ F. The air supplied in insulated ducts at relatively high velocity and pressure. The air, further, is clean and dehumidified, and reaches each display or storage cabinet at the same two supply temperatures, regardless of the size or required temperature condition of the cabinet.

Each refrigeration cabinet contains a novel air mixing and depressurizing chamber that automatically maintains the local temperature condition to which it is preset, continuously and at a constant level. The warm ($+80^{\circ}$ F.) and cold (-20° F.) air supplies are mixed in each individual cabinet in accordance to its intended use and required temperature. Such temperature presetting attains a continuous constant condition; temperature variations being eliminated as no defrost cycling is needed in the invention cabinets hereof. There thus results no deterioration of frozen foods, and a minimum of shrinkage of meats and produce.

The invention system greatly simplifies installation of multiple types of display cabinets and storage cabinets, as in a supermarket; as well as materially reduce its cost. Condensate drains and electrical connections for local fan motors and defrost heaters are eliminated in the invention refrigeration cabinets and system. Simple insulated underfloor ducts for the two system outgoing low and higher temperature air supply, referred to above, and one for the return (used) air from the cabinets, are located in the store region for such cabinets. The cabinets may be positioned at any point along the supply ducts, or simple extensions thereof, regardless of cabinet types or their requisite temperatures.

The operating temperature of each cabinet of the invention is adjustable and presettable over a wide range of temperatures. Thus, any such cabinet may be readily changed as to its operating use and temperature state. This permits flexibility of installation, as well as simplification of cabinet manufacture and stocking. An improved usable volume efficiency results in the novel improved cabinets hereof as no coils or blowers are used therein. Further, there is no restriction as to the physical size or shape of such cabinets; as the conventional evaporator cooling coils are not incorporated therein.

The overall refrigeration system hereof is cheaper to manufacture, install, operate and maintain than those of the prior art. The central unit efficiently provides the cleaned, dehumidified air at both the cold (e.g. less than -20° F.) and warm (e.g. above $+80^{\circ}$ F.) temperatures; and reprocesses the returned (used) air. The central unit forces the air through ducts at relatively high pressure and velocity. Economical insulated distribution ducts are used, as the refrigerant (e.g. Freon) is not transported to the remote cabinets.

Finally, relatively large savings result in the simplified refrigeration cabinets hereof. The air mixing and depressurizing chambers are standardized. Location of the cabinets in the store, and their individual tempera-

2

ture setting, are fully flexible. Ready change of product usage, temperature and cabinet arrangement is feasible with my invention system.

The above and other features, advantages and objects of the present invention will become more apparent from the following description of an exemplary embodiment thereof, illustrated in the drawings, in which:

FIG. 1 is a diagram of the invention refrigeration system.

FIG. 2 is an enlarged diagrammatic showing of the exemplary central refrigeration air supply unit of the invention.

FIG. 3 is a cross-sectional view through a display cabinet hereof.

Referring to FIG. 1, the central refrigeration air supply unit 15 provides air at low temperature (e.g. below -20° F.), through output duct 16; and air at higher temperature (e.g. above $+80^{\circ}$ F.), through duct 17. The air is supplied cleaned and dehumidified, and under a relatively high pressure and velocity that is optional for particular systems. The "low" and "high" temperature air under pressure is supplied to and through the cabinet areas in the market by distribution ducts 20 and 21. These distribution ducts are economically made of fiber glass, cork, Styrofoam, etc.

The air ducts 20, 21 are connected to the individual display cabinets and/or storage cabinets 25 through respective branch ducts. The return or "used" air from the cabinets 25 is returned to central unit 15 through branch ducts 26 feeding into return distribution duct 27. Duct 27 couples to the return input duct 28 of unit 15. The distribution ducts 20, 21 and 27 are directed in any desired paths, as will be understood by those skilled in the art. The three branch ducts 22, 23 and 26 for each cabinet are suitably coupled to the distribution ducts by respective tape 30, 31 and 32.

General operation of system

The air returning from the cabinets 25 through return distribution ducts 27 feeds into secondary blower fan chamber 35. The returned air is thereupon propelled along connecting ducts 36, 37, 38 to one (40) of two alternated dehumidifying-precooling-purifying chambers 40, 40'. The precooled dry air is conducted thru duct 41 into primary blower fan chamber 42. It is forced under high pressure and velocity through an evaporator cooling coil unit 43; and a portion independently through a heating coil unit 44.

The high pressure "cold" air at output duct 16 is at below -20° F. in the exemplary system; the "warm" air at line 17, at above $+80^{\circ}$ F. Different installation requirements may indicate somewhat different temperature values. The air supply is therefore at relatively high-pressure and flows at relatively high velocity through the distribution ducts 20, 21 to the various utilization cabinets 25. The air from the cabinets 25 returns through ducts 27 to complete the circuit. Details of the operation and components of central unit 15 will be set forth herein-after in connection with FIG. 2.

While one of the two dehumidifying-precooling-purifying chambers 40, 40' is in basic operation, as described hereinabove, the other one is being defrosted. Thus the chamber unit 40' in FIG. 1 is shown in its defrost phase, while unit 40 is in normal operation. A time clock control 45 is used to predeterminedly cycle the operation-defrost phasing of the units 40, 40', as detailed herein-after. Suitable motorized dampers (see FIG. 2) are used to redirect the air from chamber 35 into unit 40 or 40', and from the output of units 40 or 40' into chamber 42.

A defrost chamber 46 connects to an outside-air in-

take duct 47, and contains a blower section 48 and heater section 49. In the phase shown in FIG. 1, the defrost heated-air from chamber 46 is directed through its output duct 50 and duct 51 into unit 40'. During this cycle, heated air from chamber 46 defrosts accumulations of frost on the evaporator coils in unit 40', and exits through duct 91 to the outside air. When unit 40 is switched into the defrost cycle connection with chamber 46, the defrosted alternate unit 40' replaces unit 40 between secondary blower fan chamber 35 and primary blower fan chamber 42. This recycling or alternation of units 40 and 40' between their operational and defrost phases is initiated by the clock control 45, on a preset automatic basis; as for 30 or 60 minutes, or other interval.

The evaporator coil cooling sections in units 40, 40' and 43 are of conventional construction. A refrigerant gas, as Freon, as passed through these coils. A compressor 55 compresses the Freon gas from the return "section" line 54, in its cylinder 56. The compressed hot (Freon) gas flows into output line 57 of compressor 55 in a conventional manner. The hot gas output 57 of compressor 55 is by-passed en route to the condenser 58 in order to extract and utilize a substantial portion of its contained heat in central unit 15. Such heat utilization reduces the power requirement of the system 15, thereby improving its overall efficiency. The somewhat cooled compressed Freon returns from unit 15 to input line 59 of condenser 58; and thereupon enters a liquid Freon receiver 60 through line 61.

The liquid refrigerant (Freon) line 64 supplies the refrigerant to the several evaporator coolings coils of the system 15, as at 40, 40', 44. Liquid line 64 is fed from receiver 60 through preset valve 62 and connection line 63. The indicated compressor, condenser and receiver are of conventional construction and in the exemplary embodiment use Freon as the refrigerant. While the heat utilization by-pass to unit 15 between "outside" lines 57 and 59 is desirable, it is to be understood that the heating requirement at chambers 44 and 49 may be otherwise supplied. Thus electrical resistive heating may be used to supplement or supplant that of such by-pass.

The evaporator cooling coils of chamber unit 42 and of the dehumidifying-precooling-purifying units 40, 40' are supplied in parallel from the liquid (Freon) line 64. The coil 43 is fed by a connecting line 65 through a local expansion valve 66, with the line 67 for return to the suction line 54. The evaporator coil set of unit 40 is supplied by line 70 through a local expansion valve 71, and a return line 72; and that of unit 40' through line 73, local expansion valve 74, and return line 75.

The evaporator cooling coil 43 of chamber 42 operates on air that is dry, and therefore does not frost up. Coil 43 is directly connected across lines 54, 64 continuously. The units 40 and 40' are regularly cycled or alternated in their system operation; being defrosted when out of "circuit." Towards this end electrically operated solenoid valves 76 and 76' are respectively inserted in lines 70 and 73 to the evaporator coils in units 40 and 40'. Valve 76 is normally open; valve 76', normally closed. These are alternately cycled, electrically, by control clock 45, admitting liquid Freon to unit 40 or 40' only while it is in its "operating" phase; and shutting off such flow when in its "defrost" phase.

The heating "by-pass" arrangement for heating coil 44 in unit 42 and coil 49 in unit 46 is in "series" connection between compressed hot gas lines 57 and 59. These are connected by line 77 from line 57 to coil 49; line 78 between coils 49 and 44; and to line 59 of condenser 58 through connecting line 79. As stated hereinabove, other conventional means for heating at the chamber sections 44 and 49 may be used. The chamber sections of unit 42 containing evaporator cooling coil 43 and heating coil 44 are thermally insulated from each other.

Operation of central unit 15

FIG. 2 illustrates the central unit 15 in enlarged schematic form, in the phase wherein unit 40 is in "operation," and alternate unit 40' in "defrost." The evaporator cooling coil and heating coil circuits (FIG. 1), are omitted for clarity of presentation. The return air from the cabinets 25 enters central unit 15 through input duct 28 at chamber 35. The air passes a set of filters 81 to trap its dust particles. A secondary blower fan 80 propels the air into unit 40 or 40' in accordance with the phase setting of the ducts and motorized dampers for this purpose, as will now be described.

In the illustrated phase, the air from chamber 35 is directed from exit duct 36 through duct 37 past normally open damper 82 to line 38 into unit 40. Adjacent dampers 83 and 84 are normally closed; and damper 85, normally open. Dampers 82-85 are motor operated through control motor 86 and geared shafting 87, 88, 89 indicated by dashed lines. Alternatively each damper may be controlled by an individual motor. In this phase, also, duct 90 at cooling end of unit 40' is made to communicate directly to exhaust duct 91 through normally open damper 85; damper 84 being shut at such period.

The filtered warm return air from chamber 35 is thereupon propelled into unit 40 for dehumidifying, precooling and purifying. It passes first through a wider-spaced multi-row fin evaporator coil 92 which serves as a primary air dehumidifier and precooler. The air then passes through a closer-spaced multi-row fin evaporator coil 93, at a substantially lower temperature than coil 92, which serves as a secondary dehumidifier and precooler. The next stage in unit 40 is a bank 94 of conventional chemical dehumidifiers for the cooled air passing through, followed by an electrostatic filter 95 which optionally may contain an ozone generator.

The air thus emerges from unit 40 substantially pre-cooled, e.g. to 0° F.; relatively moisture free, clean, and odor free. In an identical manner, air when projected into unit 40' through duct 90, in the alternate cycles, is precooled, cleaned and dehumidified through components 92', 93', 94' and 95'. In the illustrated phase, the precooled air from unit 40 passes into duct 39, through normally open damper 96, and on through duct 41 into primary chamber 42. Dampers 97, 98 are normally closed in this phase, while damper 99 is normally open.

The dampers 96-99 are operated cyclically by control motor 100. They are coupled to motor 100 by suitable geared shafting as indicated, and as will now be understood. Control motors 86 and 100 are operated cyclically by clock controller 45 through electric cables schematically indicated at 101, as are solenoid valves 76, 76' (see FIG. 1). Further, instead of two central motors 86, 100, an individual motor may be used at each damper. The successive alternate cycling effects the "defrost" mode for unit 40, and the "operation" mode for unit 40'. The alternate cycle is accomplished by reversal of all the damper settings from those illustrated. Those dampers (82, 85, 96, 99) shown normally "open" in FIG. 2 are "closed"; and those dampers (83, 84, 97, 98) normally "closed," are "opened."

The basic clock controller 45 is suitably connected to operate units 40 and 40' in the alternate modes described hereinabove, through control motors 86, 100 and solenoid valves 76, 76', as will be understood by those skilled in the art. When the precooled, cleaned and dehumidified return air from unit 40 (or 40') enters duct 41, it passes into chamber 42. There the primary blower fan 105 propels this cooled dry air in part through cooling coil section 43, and in part through heating coil section 44. Blower fan 105 impels the air at high pressure and thus high velocity.

The evaporator cooling coil 43 is closely-spaced and of multi-fin construction. The enclosures 43 and 44 are suitably separated and insulated from each other. The

supply output duct 16 of primary cooling section 43 feeds distribution duct 20. The supply duct 17 of heating section 44 feeds distribution duct 21. The heating coil at section 44 is fed by the hot gas (Freon) line 78 (see FIG. 1), couples to line 59; and is in series with heater coil 49, as already described.

The alternated defrosting cycles for units 40 and 40' are preset and effected through the master clock controller 45, damper control motors 86,100, and electrical solenoid valves 76, 76', in the manner hereinabove set forth. In FIG. 2 unit 40' is shown connected in the defrost phase. The defrost system chamber 46 contains a blower fan 110 which sucks in outside air through intake duct 47 that is cleansed by air filter 111. The heating coil 49 raises the air temperature, which thereupon is propelled through duct 50 to opened damper 99 and on to unit 40' through duct 51. A defrost air temperature into unit 40' of over 80° F. is desirable.

The defrost hot-air in turn dehydrates the chemical dehumidifier component 94', and defrosts icy accumulations on the evaporator coils 93' and 92'. The now moisture-laden air in unit 40' exits through opened damper 85 and exhaust duct 91 to the outside air. A defrost cycle of 30, 60 or more minutes is commercially sufficient in the exemplary system. During the defrosting of unit 40' alternate unit 40 has been preconditioning the supply air for primary chamber 42, but accumulating moisture and frost on its coils (92, 93) in the process. Cycle change through clock controller 45 is rapidly accomplished. When unit 40 is put into "defrost" unit 40' thereupon resumes preconditioning air for primary chamber 42. The air supplied to distribution ducts 20, 21 and the cabinets 25 thus remains effectively continuous.

Operation of refrigeration cabinets

A typical display cabinet 25 of this invention is seen in plan view in FIG. 1, with its automatically functioning but preset chamber 115 shown schematically; and in vertical cross-sectional view in FIG. 3. The exemplary air mixing and depressurizing chamber 115 is disposed in a "flat" space along the bottom of the cabinet 25. It contains no motors, fans, evaporator cooling coils etc., and is therefor compact, economical, and flexible of orientation in any desired cabinet size, shape of end use.

Each cabinet is individually presettable over a wide range of operating temperatures, dependent upon its usage; and maintains its preset temperature constantly and constant. There is no shut-down period for defrosting coils in the cabinet as in prior art constructions. Hence there is no deterioration of foods stored. Typical display and/or storage cabinet (25) preset temperatures, all directly afforded by my invention, are:

	° F.
(a) For ice cream	-20
(b) For frozen foods	-5
(c) For frozen meats and fish	0
(d) For fresh meat	+32 to 36
(e) For dairy products	36 to 40
(f) For produce	40 to 45

The air mixing and depressurizing chamber 115 has two inlet air openings namely opening 116 for cold supply air; and opening 117 for the warm supply air. Cold air is supplied by inlet duct 22; and warm air, by inlet duct 23; both being tapped at 30 and 31 respectively to the distribution ducts 20, 21. The exemplary system uses cold air supply at below -20° F. and warm air supply at above +80° F., as aforesaid; and other temperature values may be instead used where desired.

A thermostatically controlled damper 118 in the warm air supply inlet 117 controls the amount of warm air entering for the required air temperature mixing for the cabinet 25. A pressure controlled damper 120 determines the amount of total mixed air (hot and warm), and its pressure, to exit from the air mixing enclosure 122. The rate

of warm air entry is regulated by the degree of opening of pivoted damper 118, directly controlled by rod 119, through bi-metallic temperature sensitive thermostat 124. Thermostat 124 is located in the region 125 of the emerging mixed air at the cabinet temperature; and when manually preset serves to maintain the air output mixture at a constant temperature level.

The air depressurizing damper 120 comprises a bowl-shaped element 126 suspended near the air inlets 116, 117 by rod 127. A pressurestat 128 controls the damper bowl 126 location with respect to the inlets 116, 117, to effect the predetermined resultant mixed air proportion and volume output and mixture temperature. Pressurestat 128 is spring-loaded, pressure sensitive, and presettable manually. The air mixing and depressurizing chamber 120 is thus held at the desired pressure and mixing temperature.

The mixed air exits from region 125 into the plenum chamber 130 along the back of the display cabinet 25. The air then exits through directional air outlet louvres 131 over the product 135 in the cabinet, in the direction indicated by arrows 132. The directed air thereupon enters return louvres 133 into the return air plenum chamber 135 along the front of the cabinet 25. The amount of return air is controlled by a manually preset damper 136 located in the air exit of the return air plenum chamber 134. The air then returns to the distribution duct 27 through its branch duct 26.

Although the present invention has been set forth in connection with an exemplary embodiment, it is to be understood that modifications may be made therein as to its arrangement, application and temperature ranges that fall within the broader spirit and scope of my invention as set forth in the appended claims.

35 I claim:

1. In combination with a closed cycle refrigeration system for refrigeration units such as display cabinets and food storage cabinets which have means for mixing hot and cold air supplied to hot and cold inlets thereof and a return outlet for the mixed air comprising a central unit with separate heating and cooling sections for air supplied to an inlet of the central unit, said central unit having hot and cold air outlets connected to and downstream of said heating and cooling sections, respectively, means for connecting said hot and cold air outlets of said central unit with the hot and cold air inlets of the storage cabinets, respectively, dehumidifying and cooling means having an inlet and outlet, means for supplying mixed air deriving from said outlet of the refrigeration unit to the inlet of said dehumidifying and cooling unit, and means coupling the outlet of said dehumidifying and cooling means as the only air supplied to the inlet of said central unit, said air supplied to said central unit from said dehumidifying and cooling means thereby being supplied to the heating and cooling sections of said central unit.

2. The system of claim 1 further including means for cleaning the air deriving from said refrigeration equipment prior to the said air being applied to the inlet orifice of said central unit, said cleaning means being disposed 60 in the path between the outlet of said refrigeration unit and the inlet of said central unit.

3. In combination with a closed cycle refrigeration system comprising a central unit with heating and cooling sections for air supplied thereto, said unit having hot and cold air outlets connected to and downstream of said heating and cooling sections, respectively, a refrigeration unit having a hot air inlet and a cold air inlet and means for mixing the hot and cold air supplied to its inlets, means for connecting the hot air outlet of said central unit with the hot air inlet of said refrigeration unit, means for connecting the cold air outlet of said central unit with said cold air inlet of said refrigeration unit, said refrigeration unit having an outlet for withdrawing the mixed air, dehumidifying and cooling means connected downstream from the outlet of said refrigeration unit to dehumidify

and cool only the mixed air deriving from said refrigeration unit, and means for connecting the outlet of said dehumidifying and cooling means as the only air inlet to said central unit so that the only air that is heated and cooled in said central unit is derived from said dehumidifying and cooling unit.

4. The refrigeration system of claim 3 wherein said dehumidifying and cooling means includes a pair of dehumidifying and cooling units, means for selectively connecting only one of said dehumidifying and cooling units between the outlet of said refrigeration unit and the inlet of said central unit, and means for defrosting the other of said dehumidifying and cooling units while the first named dehumidifying and cooling unit is connected between said refrigeration unit outlet and said central unit inlet.

5. The refrigeration system of claim 3 wherein said heating section of said central unit includes a first heat exchange coil and the cooling section of said central unit includes a second heat exchange coil, means for circulating a refrigerant in a closed loop through both of said heat exchange coils, said last named means including a compressor having its inlet connected downstream of said second heat exchange coil to be responsive to the heated refrigerant deriving from said second heat exchange coil, said compressor having an outlet connected upstream of said first heat exchange coil for supplying heated refrigerant to said first coil, means for condensing and recovering refrigerant connected downstream from said first coil and having an outlet connected upstream of the inlet for said second coil for supplying cooled refrigerant to said second coil.

6. The refrigeration system of claim 5 wherein said dehumidifying and cooling means includes a pair of dehumidifying and cooling units between the outlet of said refrigeration and the inlet of said central unit, means for

5

defrosting the other of said dehumidifying and cooling units while the first named dehumidifying and cooling unit is connected between said refrigeration unit outlet and said central unit inlet, and means connected in parallel with said second heat exchange coil for supplying the cooled refrigerant to only the dehumidifying and cooling unit connected with the inlet of said central unit.

10

7. The refrigeration system of claim 6 wherein said defrosting means include means for supplying heated air to the dehumidifying and cooling unit being defrosted, said last named means including another heat exchange coil connected in said closed loop between said compressor and said first heat exchange coil, said another heat exchange coil heating the air supplied to said dehumidifying and cooling unit being defrosted.
